United States Patent Office

Des. 221,922
Patented Sept. 14, 1971

221,922

TIRE

Harold D. Fetty, Birmingham, Mich., assignor to The Goodyear Tire & Rubber Company, Akron, Ohio

Filed Sept. 10, 1970, Ser. No. 24,918

Term of patent 14 years

Int. Cl. D12—15

U.S. Cl. D90—20

The figure is a perspective view of a tire showing my new design, it being understood that the pattern shown is repeated throughout the circumference of the tire, the opposite side being substantially the same as that shown.

I claim:

The ornamental design for a tire, substantially as shown and described.
